W. G. BLACKLIDGE.

Saw-Gummers.

No. 147,814.

Patented Feb. 24, 1874.

FIG. 4.

FIG. 1.

FIG. 5.

UNITED STATES PATENT OFFICE.

WILLIAM G. BLACKLIDGE, OF METAMORA, INDIANA.

IMPROVEMENT IN SAW-GUMMERS.

Specification forming part of Letters Patent No. 147,814, dated February 24, 1874; application filed February 6, 1874.

To all whom it may concern:

Be it known that I, WILLIAM G. BLACKLIDGE, of Metamora, Franklin county, Indiana, have invented a new and useful Improvement in Saw-Gumming, of which the following is a specification:

My invention relates to an improved form of those instruments for gumming or chambering saw-teeth, such as forms the subject of patent granted to me July 8, 1873, and in which a reaming-cylinder operates with a combined rotary sidewise and endwise movement; and my present improvement comprises a provision for varying at will the sidewise feed of the reamer. My improvement further comprises a provision whereby the fast screw may be temporarily released from its nut, so as to enable the operator to shift the wedge-slide to or fro in the frame without the delay of screwing.

In the accompanying drawing, Figure 1 is a perspective view of a machine embodying my invention, the operating-crank being broken away. Fig. 2 is a horizontal section at the line $x\ x$, the cranks being broken away. Fig. 3 is a section at line $y\ y$. Fig. 4 represents an adaptation of my releasable nut; and Fig. 5 is another modification of the same.

The frame of my machine is preferably a casting, A, having a handle, B, on top, and terminating below in two pairs of jaws, C, designed to straddle the saw-blade, and to be affixed in the desired position thereto by setscrew D and clamp-screws E E'. An L-formed groove, F, in said frame, receives my wedge-slide G, in which a straight-fluted reamer, H, is journaled obliquely to the said L-groove. The shaft I of reamer H has at each end a crank, J, and has near that end, most remote from the L-groove, a pinion, K, which gears

in a spur-wheel, L, upon a screw, M, which is journaled with the frame parallel to the L-groove. N is a half-nut, which, being depressed by screw O, engages with the feed-screw M, or may, by retraction of screw O, be disengaged from said screw M. When the half-nut N and feed-screw M are engaged, any rotation of the reamer is accompanied by an advance of the wedge-slide G within the frame A, and said reamer having thereby imparted to it an endwise and a sidewise motion, which, notwithstanding its straight flutings, gives it a shear-like and incisive action on the saw-blade. Setscrews P P', acting on bearing, enable the operator, by increasing or decreasing the relative obliquity of the L-groove and the reamer, to increase or diminish the feed.

I do not propose to restrict myself to the precise form here selected for illustration, but may vary some details thereof in non-essential particulars. For example, nut Q—whose rotation may be temporarily suspended by a pin, R, which, being inserted in a hole, a, in frame A, also occupies a notch, q, in said nut—may take the place of the releasable half-nut N.

I claim as new and of my invention—

1. In combination with the frame A F, wedge-slide G, reamer H, and gearing K L, the releasable half-nut N or its equivalent, as and for the purpose stated.

2. In combination with the elements A, F, G, H, K, L, and N, the adjustable outer bearing T to the reamer, as and for the purpose designated.

In testimony of which invention I hereunto set my hand.

WM. G. BLACKLIDGE.
